UNITED STATES PATENT OFFICE.

JOHN S. WATTERS, OF VINCENNES, INDIANA, AND ALFRED H. HAAG, OF BALTIMORE, MARYLAND.

DESIGN FOR A RADIO APPARATUS TABLE.

Application filed April 1, 1925. Serial No. 12,971. Term of patent 3½ years.

To all whom it may concern:

Be it known that we, JOHN S. WATTERS, residing at Vincennes, in the county of Knox, State of Indiana, and ALFRED H. HAAG, of Baltimore, in the county of Baltimore City, State of Maryland, both citizens of the United States, have invented a new, original, and ornamental Design for Radio Apparatus Table, of which the following is a specification, reference being had to the

accompanying drawing, forming part thereof.

The figure is a perspective view of a radio apparatus table showing our new design.

We claim,

The ornamental design for a radio apparatus table, as shown.

JOHN S. WATTERS.
ALFRED H. HAAG.
